ARNO HORN, OF BERLIN, GERMANY, ASSIGNOR TO SIEMENS & HALSKE AKTIENGESELLSCHAFT, OF BERLIN, GERMANY

MEASURED SERVICE TELEPHONE SYSTEM

Application filed November 3, 1926, Serial No. 145,924, and in Germany December 30, 1925.

The present invention relates to a circuit arrangement for a telephone coin-box station, which is adapted both for connecting to a central battery exchange and also to an automatic exchange. The circuit arrangement is so devised that calls can be made free of charge when the coin box station is called, the blocking of the circuits and of the device for collecting the coins is done by mechanical switching means without using special relays and power magnets allotted to the coin operated station.

The circuit is based upon the following idea:—

If a coin box station is called it is brought into a condition of readiness for service immediately by lifting the receiver just as with an ordinary subscriber's apparatus. The microphone receives current from the exchange battery in loop over the line *a* and *b* so that it becomes possible to conduct the speaking operations. If a call is desired from the coin box station the coin contact must be actuated by inserting a coin in the slot, so that by grounding the coin box telephone the called signal appears in the exchange or else the preselector starts; by operating the coin contact however, the microphone is cut off from the line supplying the voltage and is laid on to the other line, which receives potential only in certain condition of operation, for instance, when answering for the purpose of facilitating communication with the answering operator, or, in automatic exchanges during the selection of the no-delay exchange or of an operating position.

As soon as the desired connection has been established either, by the operator in manual exchanges, or by selection in automatic exchanges—and this can be verified by the answering of the called subscriber in his telephone—the payment key can be pressed so that a speaking connection can be obtained with the desired subscriber. On depressing the payment key the coin contacts are brought into normal, and consequently the microphone is again applied to the wire supplying the potential. Since the payment contact also grounds the coin box telephone station the feeding of the microphone takes place

over a conductor and earth. If the desired station does not reply however, then the actuation of the payment key is omitted and the receiver hung up again.

The switch hook in this case moves a coin channel which returns the inserted coin back to the subscriber as the connection has not been established. Moreover, by the actuation of the switch hook, the coin contacts are brought into the normal position, whereby the earth connection is cut off from the coin box telephone; in this manner the closing signal is given to the exchange and the supply to the microphone is disconnected.

The drawing shows two examples of the invention, viz., Fig. 1 a circuit arrangement of the coin box telephone for connection to a manual central battery exchange, and Fig. 2, a circuit arrangement of the coin box telephone for connection to an automatic central battery exchange.

1. *Traffic with the manual exchange*

In order to make the call signal appear in the exchange, a coin must be inserted as already stated, whereby the coin contacts U^1 to U^5 are actuated. Since the coin contact U^5 in the coin box station lies on earth to the *b* wire, the calling relay *AR* (Fig. 1) responds at the exchange.

1. Earth, battery, relay *AR*, back contact *tr*, conductor *b*, coin contact U^4 , choke coil $D^{2,2}$, coin contact U^5 , earth.

The operator in the exchange receives the call signal and thereupon inserts the plug of a special cord for coin box telephones, in the answering jack and after throwing over the answering key *Ab* proceeds to answer. During the time of enquiry the microphone in the coin box telephone station is supplied over the answering key so that a speaking connection with the operator is possible.

2. Earth, battery, answering key *Ab*, repeating coil *U*, plug *AS*, jack *AK*, line *a*, switch hook contact HU^1 , coin contact U^1 , microphone *M*, choke coil $D^{1,1}$, coin contact U^5 , earth.

As soon as the operator restores the answering key *Ab* to normal, current is disconnected from the line *a*, thereby rendering the micro-

phone ineffective for conversation. The calling subscriber, although he cannot converse, can hear the wanted subscriber answer since the receiver is in the following circuit:

- 5 3. Earth, condenser, repeating coil U, plug AS, jack AK line a , switch hook HU¹, coin contact U¹, microphone M, receiver F, condenser C², coin contact U⁴, line b , jack AK, plug AS, supervisory relay UR¹, repeating coil U, battery, earth.

If the desired connection has been completely established then the payment key Z is depressed so that the microphone is supplied with current. When the payment key 15 Z gets into the operated position, then the coin contacts U¹ to U⁵ are forcibly restored to normal and the coin is collected. Passing over the coin contact U² the microphone is now supplied with current over the potential 20 carrying line.

4. Earth, battery, repeating coil U, supervisory relay UR¹, plug AS, jack AK, line b , coin contact U², microphone M, choke coil Dr¹, key Z, earth.

- 25 5. By hanging up the receiver on the switch hook, all contacts are returned to normal.

In the case of a call to the coin box telephone station, the latter is made ready for service immediately by taking down the receiver from the switch hook. The microphone is then supplied in the following manner:

- 35 5. Earth, battery, repeating coil U, supervisory relay UR², connecting plug VS, connecting jack VK, line b , coin contact U², microphone M, choke coil Dr¹ and Dr², coin contact U³, switch hook HU¹, line a , connecting jack VK, connecting plug VS, repeating coil U, earth.

40 11. *Traffic with an automatic exchange*

The circuit arrangement and mode of operation of the coin box station (Fig. 2) is the same as with the manual system, only 45 that a number dial is placed in circuit.

In order that the preselector VW in the exchange may start, the contacts U¹ to U⁵ must be actuated by inserting a coin, in order that the coin box station may be connected to 50 ground. In known manner the preselector is connected in circuit by the response of the relay R. This circuit is completed as follows:

- 55 6. Earth, battery, relay R, back contact t², relay T, in the preselector (not shown here) line a switch hook HU¹, current impulse contact JK, coin contact U¹, choke coil Dr¹, coin contact U⁵, earth.

- 60 65 As soon as the preselector has found a free group selector the relay T of the preselector situated in the c wire is energized and cuts off the relay R. Relay A which is responsible for the control of the group selector, is 65 suitably influenced by the actuation of the

number disc (current impulse contact JK, number disc contact NK).

7. Earth, battery, relay A, preselector arm VW_a, front contact t¹, switch hook HU¹, current impulse contact JK, number disc contact NK, coin contact U⁶ to earth.

When selection is completed the desired subscriber replies:

8. Repeating coil U, preselector arm VW_a, front contact t¹, line a , switch hook HU¹, current impulse contact JK, coin contact U¹, receiver F, condenser C², microphone M, coin contact U⁴, front contact t³, preselector arm VW_b, repeating coil U.

If the desired connection has been established then the payment key Z must be depressed so that the microphone is connected to the voltage supply line.

9. Earth, battery, relay A, preselector arm VW_a, front contact t¹, line a , switch hook HU¹, current impulse contact JK, coin contact U³, microphone M, choke coil Dr², payment key Z, earth.

The circuit for the speaking currents is:

10. Repeating coil U, preselector arm VW_a, front contact t¹, line a , switch hook contact HU¹, current impulse contact JK, coin contact U³, microphone M, condenser C², receiver F, coin contact U², line b , front contact t³, preselector arm VW_b, repeating coil U.

At the termination of the call all contacts are returned to normal by hanging up the receiver in the switch hook. In the case where a no-delay service exchange is connected to an automatic exchange the first group selector which is accessible to the coin box station is provided with off-normal contacts k¹ to k³, these coming into the operating position upon the group selector reaching a particular vertical step. By this means on the one hand the signalling is passed on to the chief sender office, viz., that a coin box station requires a no-delay call (grounding of the line by the contact K¹): and on the other hand the microphone in the coin box station is supplied over the off-normal contact k², before the payment key is actuated, so that speaking connection is established with the chief sender office operator. If the desired connection has been established, then the payment key must be depressed in accordance with the number required by this operator.

The no-delay calls are given the preference of trunk calls. Therefore a higher charge is made than for local calls, so that several coins are to be inserted.

In order to see that due payment is made a buzzer contact SK is provided, this giving to the main sender office operator an audible signal every time the payment is actuated.

During calls free of charge with special operating places such as with the enquiry office or trouble desk, the microphone supply of the coin box telephone is likewise con-

trolled by front contacts k . These special places have assigned to them special calling numbers which begin with 0, 9, 8, the front contact k is therefore actuated in the group selector as soon as the 8th vertical step is reached. The microphone is then supplied in the following manner:

11. Earth, battery, relay B, front contact k^2 , preselector arm VWb , front contact t^3 , line b , coin contact U^4 , microphone M, choke coil Dr^2 , coin contact U^5 , earth.

If the coin box station is called, then the call may be made free of charge, the feeding of the microphone taking place as follows:

15. 12. Earth, battery in the line selector, line a , switch hook HU^1 , current impulse contact JK , coin contact U^3 , microphone M, choke coils Dr^2 and Dr^4 , coin contact U^2 , line b to earth in the line selector.

20. What is claimed is:

1. In a telephone system, a subscriber's line, paystation mechanism, a transmitter and a receiver at a substation on said line, means responsive to the removal of the receiver from the hook preparatory to the initiation of a call for connecting said transmitter and receiver in a circuit including both sides of said line in series, means responsive to the deposition of a coin in said mechanism for opening one side of said circuit and completing a circuit over one side of the line to ground at the substation, and means controlled by the subscriber for thereafter completing a circuit including both sides of the line in parallel to ground at the substation.

2. In a telephone system, a subscriber's line including a pair of conductors terminating in an exchange, a substation on said line including an impulse sender, a transmitter and a paystation mechanism, a battery connected to one conductor of the line at the exchange, means controlled by the deposition of a coin in said mechanism for grounding the line at the substation and connecting the impulse sender to said one conductor, and means controlled by the subscriber for reversing the connection of said line to the substation to connect the transmitter to said one conductor.

3. In a telephone system, a subscriber's line, paystation mechanism thereon, a substation on said line including a transmitter, one conductor of said line having battery connected thereto, means for connecting the transmitter to said one conductor, means controlled by the deposition of a coin in said mechanism for disconnecting the transmitter from said conductor, and means controlled by the subscriber for reconnecting the transmitter to said conductor.

4. In a telephone system, a subscriber's line including a subscriber's station, paystation mechanism on said line, means for ex-

tending a call therefrom, means for preventing the extension of a call until a coin is deposited in said mechanism, means controlled by the deposition of the coin for opening the circuit of the transmitter at said station, and means controlled by the subscriber at said station for thereafter collecting said coin and completing the circuit of the transmitter.

5. In a telephone system, a subscriber's station including a transmitter, a receiver and a paystation mechanism, a pair of conductors for connecting said station with an exchange, a battery at the exchange connected to one of said conductors, and means controlled by the deposition of a coin in said mechanism for completing a circuit for said transmitter over said one conductor to ground at said station and for completing a circuit for the receiver over both of said conductors.

6. In a telephone system, a subscriber's line comprising two conductors terminating in an exchange, a subscriber's station on said line including a transmitter, a receiver and a paystation mechanism, said station being adapted to send and receive calls, a battery at the exchange connected to one of said conductors, means including said mechanism controlled by the subscriber for completing a circuit for the transmitter over said one conductor to ground at said station for the sending of a call, and means controlled by the subscriber for completing circuits for said transmitter and receiver over both of said conductors for the receiving of a call.

7. In a telephone system, a subscriber's station including a paystation mechanism, a pair of conductors connecting said station with an exchange, means at said station for completing a talking circuit including both of said conductors for calls incoming thereto, and means at said station including said mechanism for completing a talking circuit including only one of said conductors for calls outgoing therefrom.

8. In a measured service telephone system, a subscriber's line, a subscriber's station on said line, a transmitter and a coin collector at said station, a source of current connected to one conductor of said line, means at said station operative upon the initiation of a call to connect the transmitter to said one conductor, means responsive to the deposition of a coin at said station to disconnect the transmitter from said one conductor to render the transmitter inoperative, and means for thereafter rendering the transmitter operative.

9. In a telephone system, a subscriber's station, a two conductor line connecting said station with a central exchange, an impulse sender and a microphone at said station, a source of current connected to one of said conductors at the exchange, coin controlled

means for reversing the line connection at the subscriber's station to disconnect the microphone from said one conductor and to operatively connect the impulse sender thereto, and subscriber controlled means for again reversing the line connection at the subscriber's station to reconnect the microphone to said one conductor.

10. In a telephone system, a subscriber's station, a microphone thereat, a line comprising a plurality of conductors connecting said station with a central exchange, coin controlled means at said station for reversing the line connection at said station to disconnect said microphone from a certain one of said conductors, and subscriber controlled means for again reversing said line connection to reconnect said microphone to said certain conductor.
11. In a telephone system, a subscriber's station, a two conductor line connecting said station with a central exchange, coin controlled means for reversing the line connection at said station, and subscriber controlled means for again reversing said connection.

In witness whereof, I hereunto subscribe my name this 12th day of October, A. D. 1926.
